United States Patent Office

Des. 214,408

Patented June 10, 1969

214,408

JEWEL BOX

Julia M. Pintea, 3838 Edinburg Drive,
Youngstown, Ohio 44511

Filed Feb. 8, 1968, Ser. No. 10,502

Term of patent 14 years

Int. Cl. D3—99

U.S. Cl. D87—1

FIG. 1

The back, the top, and the side, not shown, are substantially plain.

I claim:

The ornamental design for a jewel box, as shown and described.
